DISCHARGE DEVICE AND ELECTRODE

Howard L. Steele, Jr., North Caldwell, N. J., assignor to Westinghouse Electric Corporation, East Pittsburgh, Pa., a corporation of Pennsylvania

Application June 19, 1951, Serial No. 232,361

2 Claims. (Cl. 313—109)

1
This invention relates to lamps and, more particularly, to electrodes for low pressure discharge devices of the positive column type, such as fluorescent lamps.

Manufacturers of low pressure discharge devices of the positive column type, such as fluorescent lamps, are continually trying to increase the luminous efficiency, namely, lumens or light output per watt of power input, of the product. In this attempt, it has been found that the gas atoms surrounding the electrodes of a fluorescent lamp do not act as efficiently in generating light as do the atoms in the center of the lamp.

During the half cycle of operation on alternating current in which one electrode of a fluorescent lamp is functioning as an anode, a deficiency of positive ions occurs near this electrode or anode, and a negative space charge builds up there about. An anode voltage drop results from this space charge and is a measure of the energy which must be imparted to the random electrons, in order to overcome the repelling force of the space charge and to accelerate enough of these random electrons to the anode to supply the lamp current. It has been found that to efficiently draw the required lamp current from the random electrons in the positive column, and thus substantially minimize accelerating anode voltage drop, an anode of proper size and shape is required.

The size of the anode can be determined from the values of the random electron current as measured by Langmuir probe methods. If the anode area is large enough, the accelerating anode voltage is theoretically not necessary. Zero anode drop should be obtained when the product of the anode area and the random electron current equals the lamp current. If the anode area is above this critical value, a negative or retarding anode drop should result.

Further, the larger the anode area, the better is the luminous efficiency near the anode. However, any large anode located in front of an emitting electrode casts its shadow on the phosphor coating of the lamp envelope wall. This invention involves a compromise between an anode of large area and objectionable shadow caused by such an anode. By placing an anode having an area of the above-mentioned critical value on the axis of the envelope, the phosphor dark area produced by the anode shadow is not objectionable. The anode should be shaped to fit the equi-potential lines in the discharge which are concave toward the anode.

Hence, it has been found advantageous, accord-

2
ing to my invention, to provide in a discharge device a bullet-shaped anode having a surface area not smaller than the operating current of the device divided by the random current density in the device at the anode on the axis of the discharge where random electron current density is greatest, and in front of an electron-emissive electrode adjacent said axis, to effectively reduce anode drop and increase luminous efficiency. Because of the anode's position in the discharge, any 2537 Angstrom units radiation which is produced near the anode has a straight line path to the phosphor on the lamp wall, and is not lost within the anode. Further, the bullet-shape of the anode fits the equi-potential lines in the discharge which are concave toward the anode.

In its general aspect, the present invention has the object of overcoming the aforementioned disadvantages of the prior art low pressure discharge devices of the positive column type.

The principal object of the invention is to provide a bullet-shaped anode on the axis of the discharge and in front of a conventional electron-emissive electrode of a low pressure discharge device of the positive column type, to effectively reduce anode voltage drop and to increase luminous efficiency.

Another object is to provide a bullet-shaped anode for a low pressure discharge device of the positive column type which as much as possible avoids augmenting the dark area of the phosphor caused by the anode shadow.

An additional object is to provide a bullet-shaped anode for a low pressure discharge device of the positive column type which fits the equi-potential lines in the discharge of the device.

A further object is to provide a bullet-shaped anode for a low pressure discharge device of the positive column type which permits 2537 A. U. radiations produced near the anode to travel in straight lines to the phosphor coating on the envelope of the device.

Other objects and advantages of the invention will appear to those skilled in the art to which it appertains as the description proceeds, both by direct recitation and by implication from the context.

Referring to the accompanying drawing, in which like numerals of reference indicate similar parts throughout the several views:

Fig. 1 is a fragmentary elevational view of a discharge lamp with parts in axial section, and showing the bullet-shaped anode of my invention;

Fig. 2 is a transverse sectional view on line II—II of Fig. 1, in the direction of the arrows;

Fig. 3 is a perspective view of one of the mounts of the lamp of Fig. 1;

Fig. 4 is an axial sectional view of the bullet-shaped anode of my invention;

Fig. 5 is a perspective view similar to Fig. 3, but showing an alternative embodiment of the bullet-shaped anode of my invention;

Fig. 6 is a sectional view, similar to Fig. 4, but showing the alternative anode embodiment of Fig. 5;

Fig. 7 is a perspective view similar to Figs. 3 and 5, but showing a further alternative embodiment of the bullet-shaped anode of my invention.

Referring now to the drawing in detail, and particularly to Fig. 1, the reference numeral 10 designates a low pressure discharge device of the positive column type. While a fluorescent lamp has been shown as an embodiment of such a device, it will be understood that use of this invention is not restricted to fluorescent lamps. This device or lamp 10 comprises a vitreous envelope 11 suitably coated with a phosphor and containing an ionizable medium, for initiating and sustaining a discharge, such as an inert gaseous fill at low pressure admixed with mercury vapor, and oppositely positioned electrode mounts 12 hermetically sealed in each end thereof. A suitable base 13 is affixed to the envelope at each end.

The mount 12 shown in Figs. 2 and 3 consists of a filamentary cathode 14, supported adjacent the axis of the lamp discharge by leading-in conductors 15 and 16 sealed through the press 17 of a vitreous stem 18, and a bullet-shaped anode 19.

Each bullet-shaped anode 19, the cylindrical portion of which is about $\frac{3}{8}$ " in diameter, with a semi-spherical end portion or dome $\frac{1}{8}$ " in radius at each end, and approximately $\frac{3}{4}$ " long, is made of a suitable reasonably-low work function material, such as nickel or misch metal. It is hollowed out to reduce its mass and has its outer portion formed as a hollow neck-like projection 20 (Fig. 4) for joining to an L-shaped metallic conductor 21.

Each anode is mounted on the axis of discharge where the electron concentration or random electron current is a maximum, by means of said connector 21, and with the dome tip for example, about $\frac{3}{4}$ " in front of its cathode 14. The connector 21 is secured, as by welding, to one of the leading-in conductors 15 and 16. The dome-like forward or inner portion of each anode fits the equi-potential lines 22, shown in Fig. 1, in the discharge of lamp 10. This mounting arrangement of the axial anodes 19, and adjacent cathodes 14 located outwardly from their anodes, minimizes the dark area of the phosphor caused by the anode shadow, and permits 2537 Angstrom units radiations produced near the anode to travel in straight line paths to the phosphor.

A suitable exhaust hole 23 (Fig. 4) in the wall of the anode permits evacuation of the hollow interior of the anode during exhaust of said lamp 10.

If the product of the surface area of anode 19 and the random current density equals the current of the lamp 10, the anode voltage drop should be zero. Examples of this critical value of anode surface area, which is not smaller than the operating current of lamp divided by the random current density of the lamp at the anode, for a given lamp current, given gas fill, and given

gas fill pressure in a fluorescent lamp, are summarized in the following table:

Gas Fill	Gas Fill Pressure (mm.)	Lamp Current (ma.)	Random Electron Current Density On the Axis in ma./cm. ²	Area in cm. ² Which Should Give Zero Drop
Argon.....	3.6	520	356	1.42
Do.....	3.6	420	296	1.42
Krypton.....	2.0	520	484	1.07
Do.....	2.0	420	397	1.06

As an alternative embodiment, the anodes of my invention may be solid and bullet-shaped as shown in Fig. 6 and designated by the reference numeral 19^a. A suitable axial hole is provided at one end of anode 19^a for affixing, as by welding or by a threaded connection, a metallic dummy lead 24 which is suitably of larger diameter than the connector 20 of Fig. 3 and Fig. 4, to better support the increased mass of anode 19^a. Except for the use of a suitable intermediate connector 25, between the connector 24 and one of the conductors 15 and 16, the surface area of anode 19^a is dimensionally the same, and it is mounted similarly in stem 18, as shown in Fig. 5, and functions in lamp 10 in the same manner as anode 19.

In Fig. 7, there is shown a further embodiment of my invention, namely a hollow cup-like bullet-shaped anode 19^b which is mounted axially on stem 18 by means of the leading-in conductor 16 with the dome tip, for example, about $1\frac{1}{4}$ " from the also axially mounted cathode 14. As in the case of the other above-mentioned embodiments, the outer surface area of anode 19^b is dimensionally the same as anodes 19 of Fig. 3 and 19^a of Fig. 5.

Thus it will be seen from the foregoing description that I have provided bullet-shaped anodes 19, 19^a or 19^b on the axis of the discharge and in front of filamentary cathodes 14 of a low pressure discharge device 10 of the positive column type to effectively reduce anode voltage drop and to increase luminous efficiency. This arrangement of the bullet-shaped anodes in front of the adjacent conventional cathodes 14 minimizes the dark area of the phosphor caused by the anode shadow, and permits mercury resonance radiations produced near the anode to travel in a straight line path to the phosphor. The dome-like end section of each bullet-shaped anode 19 is designed to fit the equi-potential lines 22 of the pressure discharge device 10.

While preferred embodiments of my invention have been disclosed, it will be understood that modifications may be within the spirit and scope of the appended claims.

I claim:

1. A low pressure discharge device of the positive column type comprising a vitreous envelope having a phosphor coating thereon, oppositely disposed electrode mounts hermetically sealed to said envelope, and an ionizable medium in said envelope for initiating and sustaining a discharge; at least one of said electrode mounts comprising a stem having at least two leading-in conductors, a filamentary cathode supported on said leading-in conductors adjacent the axis of the discharge of said device, and a bullet-shaped anode on the axis of the discharge on one of said leading-in conductors of said device inwardly of said cathode and having sufficient surface area to minimize anode voltage drop in said device, said area being larger than the operating cur-

rent of the device divided by the random current density of the device at the anode.

2. In a low pressure discharge device of the positive column type, an electrode mount comprising a stem having at least two leading-in conductors, a filamentary cathode supported on said leading-in conductors adjacent the axis of said device and a bullet-shaped anode on the axis of said device on one of said leading-in conductors inwardly of said cathode, and having sufficient surface area to minimize anode voltage drop in said device, said area being larger than the operating current of the device divided by the random current density of the device at the anode. 15
